(57) **CLAIM**

The ornamental design for a rear portion of removable
tweezers for a multipurpose tool, as shown and described.

DESCRIPTION

FIG. 1 is an isometric view from the upper right rear of a rear
portion of removable tweezers for a multipurpose tool,
showing my new design, wherein the outer, or front, end
portions of the tweezers arms, shown in broken line, are
included merely for illustrative purposes and form no part of
the claimed design;

FIG. 2 is a right side elevational view thereof, the left side
elevational view thereof being a mirror image of this view;

FIG. 3 is a top plan view of the portion of a removable
tweezers for a multipurpose tool shown in FIG. 2;

FIG. 4 is a bottom plan view thereof;

FIG. 5 is a front end elevational view thereof; and,

FIG. 6 is a rear end elevational view thereof.
